UNITED STATES PATENT OFFICE.

WILLIAM A. ALLEN, OF NEW YORK, N. Y., ASSIGNOR TO THE ALLEN AUTO SPECIALTY COMPANY, OF NEW YORK, N. Y., A CORPORATION OF NEW YORK.

RADIATOR JACKET.

Application filed September 26, 1919. Serial No. 326,585.

To all whom it may concern:

Be it known that I, WILLIAM A. ALLEN, a citizen of the United States of America, residing at New York city, in the county of 5 New York and State of New York, have invented certain new and useful Improvements in Radiator Jackets, of which the following is a specification.

My invention relates to radiator jackets, 10 and particularly to a combined jacket and shutter device, the object of my invention being to provide a useful accessory for automobiles, having certain features of novelty and utility hereinafter pointed out or shown 15 in the accompanying drawings, in which—

Fig. 1 is a front elevation of a jacket in which my invention is embodied in one form;

Fig. 2 is a rear elevation thereof;

Fig. 3 is a side elevation thereof;

Fig. 4 is a similar view of a portion of the appliance, but showing the shutter and associated parts in different position;

Fig. 5 is a side elevation of the operating 25 lever at the dash;

Fig. 6 is a partial section through a portion of the shutter and upper part of the jacket; and

Fig. 7 is a fragmentary perspective of one 30 of the shutters.

The present appliance is shown as a combined radiator jacket and shutter, although certain of its features of construction are applicable to either a jacket or a shutter 35 alone disassociated from the other.

The jacket proper comprises a front piece 10 of pantasote or the like, lined on its inner face with felt 11, or other good non-conductor of heat. Attached to the top and 40 side margins of the front piece and extending back at right angles thereto is a strip of pantasote 12, covering the body of the radiator and similarly lined at 13. A hole 14 is provided to receive the radiator filling 45 spout 15 (Fig. 3). To the rear margin of this strip 12 are secured several soft metal clips 16 adapted to be bent around the usual flange (not shown) at the back of the radiator and on which the hood rests. The clips 50 16 thus afford readily attachable and detachable means for securing the jacket.

The front piece 10 of the jacket is centrally cut out to afford a large opening at the front of the radiator grid (not shown). Re- 55 enforcing bars 17 of strap metal are ar-

ranged at the inner margins of this opening and receive the screw bolts 18 (Fig. 6) by which the angle straps 19 are secured at the margins of the holes on the outer face of the front piece. These angle straps constitute the frame in which the slats 20 of the shutter are pivoted.

At one side and adjacent the top of the frame 20 I secure a bracket 21 having pivoted thereto at 22 the operating lever 23 for 65 the shutter slats. Connected to this lever at 24 is the shutter bar 25 extending vertically at the sides of the slats and pivoted at 26 to lugs 27 thereon, so that they move in unison. A strong spring 28 coiled on the stud 29 en- 70 gages with one leg 30 the stop 31, while its other leg 32 bears against the pin 33 on lever 23 and tends constantly to force the latter downward into the position shown in Fig. 4 in which the shutters are closed. 75

Dual means are provided to move the shutter to open position. The first of these means comprises a thumb screw 34 carried by the lever 23 and working in the arcuate slot 35 in the bracket 21. This screw serves 80 not only as means for swinging the lever 23, but also for clamping it in adjusted position. The second means comprises a wire, chain or the like 36, connected at 37 to the outer end of the lever 23 and passing 85 through the radiator grid (not shown) to the dash, where it is connected to a hand lever 38. The latter is pivoted at 39 to a bracket 40 and carries a spring pin 41 adapted to engage in any one of a series of holes 90 42 punched in the bracket. Both operating means thus make it possible to secure the shutter opened to any desired extent, while on release of these means the spring 28 automatically closes the shutter again. 95

While not necessary, it is advisable to provide a sleeve for the wire 36 at the point at which it passes through the radiator grid, thus guarding the latter against wear. The shutter slats 20 are preferably made from thin sheet metal, lined on the inner face with felt 43 (Fig. 7), which is held in place at the free margin of the slat by the folded back edge 44 of the metal. The inner margin 45 of the slat is rolled over a stiffening rod 46, the projecting ends of which form the pivots on which the slats are mounted in the frame 19.

This combined jacket and adjustable shutter is readily affixed to or removed from the 110

2
radiator; the dual operation of the shutter eliminates the necessity for carrying back the operating wire to the dash where this is not possible or desired. The construction 5 as a whole is durable and serviceable, while at the same time economical to manufacture.

Various detail modifications of construction will readily occur to those skilled in the art, which do not depart, however, from 10 what I claim as my invention.

I claim as my invention—

1. For use with an automobile having a radiator and a dash spaced therefrom, a combined jacket and shutter for the radiator, 15 comprising a fabric jacket having a front opening facing the radiator grid, reenforcing strips on the inner face of the jacket front at the margins of said opening, a shutter frame on the outer face of the jacket 20 front, securing means therefor engaging the reinforcing strips at the margins of the opening, a shutter mounted in the frame, a sector secured to said frame, a shutter-operating lever pivoted to the sector, and means 25 for operating said lever at the sector, said lever having an extension adapted to receive an operating connector leading to the dash.

2. For use with an automobile having a radiator and a dash spaced therefrom, a combined jacket and shutter for the radiator, 30 comprising a fabric jacket having a front opening facing the radiator grid, reenforcing strips on the inner face of the jacket front at the margins of said opening, a shutter frame on the outer face of the jacket 35

front, securing means therefor engaging the reenforcing strips at the margins of the opening, a shutter mounted in the frame, a sector secured to said frame, a shutter-operating lever pivoted to the sector, and 40 means for operating said lever at the sector, said lever having an extension adapted to receive an operating connector leading to the dash, together with a stud on said sector, a coil spring mounted on said stud and 45 having an arm engaging the operating lever and tending constantly to hold said lever in shutter-closing position.

3. A combined jacket and shutter for radiators comprising a fabric jacket having a front opening facing the radiator grid, re-enforcing strap metal on the inner face of the jacket front at the margin of said opening, a shutter frame on the outer face of the jacket front, securing means therefor 50 engaging the reenforcing strap metal, and a shutter mounted in said frame.

4. A combined jacket and shutter for radiators comprising a fabric jacket having a front opening facing the radiator grid, re-enforcing strap metal on the inner face of the jacket front at the margin of said opening, angle straps mounted on the outer face of the jacket front, securing means therefor 55 engaging the reenforcing strap metal, and a shutter mounted in said frame.

In testimony whereof I have signed my name to this specification.

WM. A. ALLEN.
